[58] Field of Search ..... Plt. 87.4

Primary Examiner—James R. Feyrer

[57] ABSTRACT

A new variety of hybrid lily plant bearing large upright-facing flowers of excellent form and long persistence,

both on the plant and as cut-flowers. The flowers of the new plant are particularly characterized by their pink coloration shading into a small yellow band at the midrib, their lightly ruffled margins, their large size and substance, their upright to semi-upright orientation, and the sharply ascending pedicels of the upper flowers. This combination is completely new in the Oriental hybrid divisions of lilies suited to forcing and to mass commercial cultivation. The variety is highly resistant to fusarium disease and shows tolerance of virus. The bulbs may be precooled and forced for cut-flower production. The clone is vigorous and is a good grower and propagator.

1 Drawing Sheet

1

BACKGROUND OF THE INVENTION

My new variety of lily plant originated as a seedling which first flowered in 't Zand, Netherlands, in 1987. The breeding efforts had as their objective the production of large-flowered upright and semi-upright Oriental hybrids in bicolored combinations of pink, white, and yellow, with pigmented papillae, suited to forcing into flower out of season, heretofore unknown in the lily breeding art.

I achieved the desired objective by intercrossing selected upright and semi-upright pink Oriental seedlings suited to forcing for year-round use as cut-flowers and carrying the recessive gene for a small yellow band.

The flowers of my new lily are characterized by an upright orientation, large size and broad-tepalled "bowl-shaped" form, usually thick substance, ruffled tepal margins, and a distinctive soft pink coloration shading into a small yellow banded midrib, with deeper magenta-rose papillae, unique among Oriental hybrid lilies. The pedicels of the upper flowers are sharply ascending. It possesses usually strong, stout stems. In addition, the clone possesses to a high degree desirable characteristics of hybrid vigor. The clone is a good grower and propagator, as observed at 't Zand, Netherlands, and at Salem, Oreg.

My new variety of lily plant has been asexually reproduced by me and under my direction at 't Zand, Netherlands, and at Salem, Oreg. Successive generations produced by natural propagation from bulbets, by bulb scale propagation, and by tissue culturing from bulb scale explants have demonstrated that the novel and distinctive characteristics of my new variety are fixed and hold true under asexual propagation from generation to generation.

DESCRIPTION OF THE DRAWING

My new variety of lily plant is illustrated in the accompanying photographic drawing, which shows the open bloom in full color and illustrates the flower form, the tepal arrangement, the ascending pedicels connecting the flower to the stem, and in particular the novel and distinctive flower form with lightly ruffled tepal margins, its upright to semi-upright orientation, and its soft pink coloration shading into a small yellow banded

2

midrib, accented by deeper magenta rose papillae on the basal half of each tepal.

DESCRIPTION OF THE NEW VARIETY

5 The following is a detailed description of my new variety of Oriental hybrid lily, with nomenclature according to the *International Lily Register* (Royal Horticultural Society of London, Second Edition, 1969), and with color designations according to the Colour Chart 10 of The Royal Horticultural Society, published by the Society in 1966.

The Plant

15 Origin: Seedling.
Seed parent: Selected unnamed Oriental hybrid seedling.
Pollen parent: Selected unnamed Oriental hybrid seedling.
20 Commercial classification: Hybrid Lilium clone.
Horticultural classification: Division VII-B, bowl-shaped Oriental hybrid lily, according to the Horticultural Classification of Lilies, Royal Horticultural Society of London.
25 Form: Single stem, erect and stately.
Height: 70 to 125 cm from bulbs 14 to 18 cm in circumference, provided their light levels are adequate; low light levels may cause "stretching."
Growth: Vigorous and upright.
30 Foliage quantity: Abundant.
Size of leaf: Unusually broad, 4 to 7 cm wide $\times$ 10 to 14 cm long.
Shape of leaf: Lanceolate (pointed).
Texture: Leathery and glossy.
35 Color: Medium green, lighter on lower side.
Bulb size: Any size, ranging to 25 cm circumference commercially.
Bulb color: White, with flushes of pink or yellow after exposure to light.

The Bud

40 Form: Obtuse, ovoid, and long.
Size: 9 to 12 cm long and 10 to 14 cm in circumference just prior to opening.

Opening: Bud opens slowly, in response to morning light; this takes about one hour.

Color: Ivory white to soft pink (R.H.S. C.C. red 56 D to red-purple 62 D), with pale green midribs.

Peduncle: Averages 4 to 6 cm, but it may elongate if light levels are too low or if bulbs have been improperly stored prior to forcing. Color is medium green with very light plum overlay.

The Flower

Blooming habit: Annually in midseason; flowers once and profusely.

Size: Flowers are large-sized, averaging 15 to 20 cm in diameter, reflexing at the tips on the second day to 15 to 18 cm in diameter. The tepals are broad: outer tepals are 2.5 to 3.25 cm wide, and the inner tepals are 4.5 to 5 cm wide.

Borne: In a single racemic inflorescence producing 4 to 8 flowers from a bulb 14 to 16 cm in circumference.

Shape: Form a broad bowl shape by the second day after opening, with the "bowl" 10 cm deep.

Tepalage: Typical of genus *Lilium*, with 6 imbricated tepals.

Tepal color: R.H.S. C.C. red 55 B-D to red-purple 65 C-D, depending upon growing temperatures and light levels, shading into a small yellow ray of R.H.S. C.C. 6 C to 9 C, extending 4 to 8 cm from the green nectaries. The pink color is slightly affected by temperature and light levels; it decreases with high temperatures and low light levels.

Tepal spotting: The basal half of each tepal is spotted with magenta rose papillae of moderate size.

Tepal longevity: Tepals stay on stems about three weeks.

Pedicel length: Average 8 to 12 cm long.

Pedicel color: Medium green with very light plum overlay.

Pedicel form: Sturdy and ascending, up to 60 degrees from the horizontal in the upper flowers.

Color changes: Flowers become slightly lighter and a more lavender-toned pink as the flowers age. Low light levels and extreme heat may cause the pink pigmentation to decrease.

Appearance: Flower is shiny.

Disease resistance: The flower and plant are resistant to disease; in particular, they are resistant to Fusarium bulb rot and Botrytis blight.

Fragrance: Light sweet fragrance.

5 Lasting quality: The flower is long lasting, both on the plant and as a cut-flower.

The Reproductive Organs

Stamens: Arrangement typical of genus *Lilium*. Six stamens with soft green to palest pink filaments 8 to 10 cm long.

Pollen and anthers (dehisced): R.H.S. C.C. greyed red 178A to 182 A.

Pistil: One in number, 8 to 10 cm long.

15 Stigma: Soft greenish-white to greyed purple R.H.S. C.C. 186 C/D, large in size.

Characteristics of ovary: Characteristic of genus *Lilium*.

The Fruit

Fertility: The fruit bears fertile seed.

Shape: Ovoid.

Color at maturity: Soft brown, sometimes overlaid with soft plum.

25 My new variety of Oriental hybrid lily most nearly resembles 'Joy,' but it has much larger and thicker, more bowl-shaped flowers with more ruffled tepal margins. Its flowers have a more conspicuous yellow midrib, as well as a greater number of more deeply colored papillae. Its pedicels are more sharply ascending, and its inflorescence bears more flowers.

I claim:

35 1. A new and distinctive variety of Oriental hybrid lily plant substantially as herein shown and described, characterized by its high resistance to disease; its tolerance of virus; its vigorous growth and rapid natural propagation; the excellence of its flower form, size, and substance; its versatility both as a garden plant and as a cut-flower producer from pre-cooled bulbs forced under glass out of season; and in particular by its unique upright to semi-upright flowers with sharply ascending pedicels, its lightly ruffled tepal margins, and its soft pink coloration shading into a yellow midrib, accented with noticeable magenta rose papillae on the basal half of each tepal, a combination unique among Oriental hybrid lillies suited to forcing and to mass commercial cultivation.
